UNITED STATES PATENT OFFICE.

HIRAM S. LASHER, OF NEW YORK, N. Y., ASSIGNOR TO UNDERWOOD ELLIOTT FISHER COMPANY, OF NEW YORK, N. Y., A CORPORATION OF DELAWARE.

TYPEWRITING MACHINE.

Application filed November 12, 1925. Serial No. 68,553.

This invention relates to a web-typing machine of the well-known Underwood type. In said machine, a longitudinally fan-folded web is interleaved with carbons, and is inserted around the platen of the machine to be typed upon. After typing each form, the platen is elevated to straighten out the web and the carbons are shifted to be presented to a fresh form. Then the platen is lowered again to its typing position to tear off the typed form.

Heretofore slitting knives mounted on carbon-blades have been provided, the slitting of the plies being accomplished at the shifting of the carbons. This is objectionable because it takes considerable power to simultaneously slit all the plies, and, since the web is held with one hand during the carbon-stripping operation, there are apt to be faulty registrations of the forms on the several plies of web. Moreover, the slitting extends far back from the platen, which is another source of creeping of the plies and trouble with registration.

In this invention, there is provided a slitting truck, which is operative independently of the carbon-carrier, the slitting truck being automatically controlled during the platen elevating and lowering operations. The truck is reciprocable towards and away from the platen between the carbon-carrier and the platen itself. It is connectible to the platen-frame, so that, when the platen is elevated, the truck need not move, but, when the platen is lowered, the truck will be driven to the rear of the machine away from the platen, slitting the folds of web. The connection between the elevated platen and the splitter truck is effective during the swing of the platen down to typing position, to thrust back the splitter truck automatically.

There may be a relative adjustment such that the carbon-carrier may pick up the splitter truck at any selected point, this adjustment co-operating with the adjustable rear stop for the carbon-carrier, so as to accommodate a variety of work.

Other features and advantages will hereinafter appear.

In the accompanying drawings,

Figure 1 is a sectional elevation of an

Underwood continuous biller having the invention applied thereto, and shows the web in typing position.

Figure 2 is a diagrammatic view, showing the platen in elevated position, and the means for drawing a slitting truck to its normal position.

Figure 3 is a cross-section, in elevation, through the supports for the web-splitting knives.

Figure 4 is a plan, showing all the mechanism in position corresponding to Figure 1.

Figure 5 is a diagrammatic view, showing the carbon-stripping operation and the gagging of the web.

Figure 6 is a diagrammatic view, showing the idle swing of the platen preparatory to moving the slitting truck to separate the plies of the web.

Figure 7 is a diagrammatic view, showing the stop-device for controlling the travel of the slitting truck.

Figure 8 is a dismembered perspective view of the slitting truck-guiding means, and shows also the means for removing the truck.

Figure 9 is a cross-sectional view through a portion of the stop-device control mechanism.

According to the method of handling the work in this invention, a multi-ply longitudinally fan-folded web 10 is threaded between carbons 11, which are mounted upon carbon-blades 12, and the leading edges of both the carbons and the web are squared so as to form a pack, which is inserted down a rear table 13 and under a platen 14, which cooperates with feed-rolls 15 to line-space the web. Then the platen is rotated to position the web for the first line of typing on the first form, and other lines are typed on the form by means of type-bars 16, the platen being subsequently elevated to straighten out the web and to gage it to form length against a front gage 17. The end of the web is held against the gage while the carbon-carrier is moved back by means of a handle 18, thereby presenting the carbons to a fresh form of the web.

In order that the plies of the web may be separated before being inserted around the platen, there is provided a slitting truck, which comprises a plate 19 arranged to recip-

rocate on rails 20 mounted on the platen-frame of the machine. Upon said plate there is provided a series of knives 21, preferably mounted on studs 22, the knives being threaded between the plies of the web in a manner to afford the splitting or slitting of the plies when the truck is moved backwardly. Said knives are laterally adjustable to accommodate different widths of webs, and are arranged to be locked in different positions along rails 23, which may be fastened to the plate 19.

After finishing the typing of a form, the platen is elevated to permit stripping of the carbons, and is again lowered to typing position, and at this manipulation of the platen it is desired to operate the slitting truck mechanically. To this end, there is provided mechanism which may include a tube 24 and a shaft 25 telescopically mounted in said tube. The forward end of the shaft may be pivotally mounted at 26 on a plate 27, which is fast to one of the end plates 28 of the platen-frame. The tube or guide is pivotally mounted at 29 on an upwardly-extending bracket 30 forming an integral part of the plate 19.

Referring to Figure 5, in which the extreme forward position of the slitting truck is shown, it will be noted that at the end of the tube 24 there is provided a pawl 31 mounted on said tube and engaging with a notch 32 at the end of the shaft 25.

In Figure 6, the platen is shown in its midway position while being swung downwardly on rock-shaft 33, at which position the end of the shaft engages with a pawl 34, which is slidably mounted on said tube and is settable thereon by means of a finger-screw 35. At this point, by further swinging the platen downwardly to be lowered to its normal position, the end of the shaft 25 engages with the pawl and forces the tube backwardly, thereby carrying the slitting truck with it to slit the plies of the web.

In Figure 7, the platen is shown in its normal position, in which a lower extension 36 of the pawl 34 engages with a pin 37, which is mounted on a plate 38 fast on one of the rails 20, and, owing to the interference of said pin 37, said pawl is rocked on a pivot 39, thereby releasing the end of the shaft which collapses further into the tube.

In Figure 9, a cross-sectional view is shown of the pawl, the tube and the shaft, and it also shows a sliding block 40 for supporting the pawl and the interfering pin for releasing the same. This view is self-explanatory and shows only one form of the invention, it being understood that any other form would be suitable provided the pawl was made slideable and settable on the tube. The pawl is held in its normal position by means of a spring 41.

In the Underwood fan-fold biller, it has

been customary to provide means whereby the web and the carbons can be withdrawn from the machine, so that another web having other types of forms printed thereon may be used. This being an excellent feature of said machine, it is not desired to destroy it by the use of the slitting truck as a separate unit. To this end, there is provided mechanism for detaching the plate 19 from a carrying truck 42. Said mechanism includes a pair of pins 43 fast to the plate 19, the pins entering holes in the truck 42 and being slotted for engagement with clamping members 44 pivotally mounted at 45 on said truck 42. In this manner it will be seen that it is an easy matter to withdraw the web by simply releasing the locking members and withdrawing the plate upon which the knives are mounted. The carbon-carrier is mounted on a truck 46 in a similar manner, the clamping elements being similarly numbered for easy identification. Both the carbon-carrying truck 46 and the slitting truck 42 are provided with wheels 47 designed to roll on the rails 20. The wheels are revolvably mounted on frames 48, which frames are secured beneath the trucks by means of rivets 49.

In order that the knives may be individually threaded between the plies of the web, and in order that the knives may be positioned to accommodate webs of different widths, the knives are pivotally mounted on the studs 22, which are provided with square heads 50 designed to slide between the rails 23. The knives may be individually swung into or out of engagement with the web, and may be locked in either position by means of finger-pieces 51. In order that the knives may be held at the proper angle when swung to their effective positions, there may be provided an angular plate 52 which serves as a backing for the knives. Said plate 52 is designed to slide between the rails 23 and may be locked in position when the finger-pieces 51 are tightened to lock the knives.

When lowering the platen to its normal position, the web is wrapped therearound, thereby drawing on the web and its associated carbons, but, since the slitting truck is moved rearwardly while the web is pulled forwardly, it will be seen that the slitting truck does not need to travel the full length of a form, considerably less travel being enough to completely slit the form. For clearness, in illustrating this condition, a stop-gage 53 is shown, which co-operates with the carbon-carrier to limit its travel, said gage being shown in Figures 5 and 7, the latter showing the carbon-carrier moved forwardly away from the gage.

Means are also provided in this invention for laterally guiding the web to the platen, said means including a pair of side gages 54 adjustably mounted upon a cross-rod 55 and a second pair of gages 56 adjustably mounted on blocks 57 to which the blades 12 are secured.

Variations may be resorted to within the scope of the invention, and portions of the improvements may be used without others.

Having thus described my invention, I claim:

1. The combination with a typewriting machine having a platen, means for guiding a longitudinally fan-folded web to said platen, means including a carbon-holder for shifting the position of carbons interleaved with the plies of said web, a device for displacing the platen preparatory to the carbon-shifting operation, of means for slitting the plies of the web previously to the insertion of the web around the platen; said last-mentioned means including a truck arranged to reciprocate towards and away from the platen, and means operatively connected to said displacing device for operating said truck relatively to said carbon-holder at the operation of the platen-displacing device. 19
2. The combination with a typewriting machine having a platen, means for guiding a longitudinally fan-folded web to said platen, means including a carbon-holder for shifting the position of carbons interleaved with the plies of said web, a device for displacing the platen preparatory to the carbon-shifting operation, of means for slitting the plies of the web previously to the insertion of the web around the platen, said last-mentioned means including a truck arranged to reciprocate towards and away from the platen, and means operatively connected to said displacing device for operating said truck relatively to said carbon-holder at the operation of the platen-displacing device, and after the completion of the carbon-shifting operation, said truck having knives adjustably mounted thereon, said knives being lockable in either effective or ineffective positions. 30
3. The combination with a typewriting machine having a platen, means for guiding a longitudinally fan-folded web to said platen, means for shifting the position of carbons interleaved with the plies of said web, and a device for displacing the platen preparatory to the carbon-shifting operation, of means for slitting the plies of the web previously to the travel of the web around the platen, said last-mentioned means being connected to said displacing device to be operated during the lowering of the platen to its normal position, after the completion of the carbon-shifting operation. 50
4. The combination with a typewriting machine having a platen, means for guiding a longitudinally fan-folded web to said platen, means for shifting the position of carbons interleaved with the plies of said web, and means for displacing the platen preparatory to the carbon-shifting operation, of means at the intake side of the platen for slitting the plies of the web, including a truck arranged to move toward the platen at the advance of 60
- the web, and means connecting said truck to said displacing means to be moved away from the platen and slit the web during the latter part of the platen-restoring operation after the completion of the carbon-shifting operation. 70
5. The combination with a typewriting machine having a platen, around which a web is passed to be typed upon, said web having a plurality of fan-folded plies interleaved with carbons, a carbon-carrier and means for elevating the platen preparatory to shifting the carbons, of means controlled by the platen-displacing means to split the plies of the web at the folds thereof, said splitting means mounted between said platen and said carbon-carrier and movable relatively to the latter. 75
6. The combination with a typewriting machine having a platen, around which a web is passed to be typed upon, said web having a plurality of fan-folded plies interleaved with carbons, a carbon-carrier, and means for elevating the platen preparatory to shifting the carbons, of means controlled by the platen-elevating means to split the plies of the web at the folds thereof, said last-mentioned means including a truck arranged to reciprocate between the platen and the carbon-carrier, and knives on said truck interleaved with the plies of the web in a manner to separate the plies of the web when the truck is moved away from the platen. 85
7. The combination with a typewriting machine having a platen revolvably mounted in a displaceable platen-frame, means for conducting a multi-ply longitudinally fan-folded web to the platen, and means for shifting carbons between the plies of the web to fresh portions of the web during the platen-displacing operation, of means for splitting the plies of the web, said last-mentioned means including a truck arranged to reciprocate toward and away from the platen, and means for operatively connecting said truck to the platen-frame in a manner to cause the truck to be displaced away from the platen when the platen-frame is lowered to its normal position, after the completion of the carbon-shifting operation. 100
8. The combination with a typewriting machine having a platen revolvably mounted in a displaceable platen-frame, means for conducting a multi-ply longitudinally fan-folded web to the platen, and means for shifting carbons between the plies of the web to fresh portions of the web during the platen-displacing operation, of means for splitting the plies of the web, said last-mentioned means including a truck arranged to reciprocate toward and away from the platen, and means for operatively connecting said truck to the platen-frame in a manner to afford the truck to be displaced away from the platen when the platen-frame is lowered to its normal position, said last-mentioned means including a 110
- 120
- 125
- 130

tubing pivotally mounted on said truck, a collapsible shaft in said tubing, said shaft being pivotally mounted on the platen-frame, and means for connecting the end of the shaft with the tubing, so that the truck will be picked up after the platen has been partly lowered to its normal position.

9. The combination with a typewriting machine having a platen revolvably mounted in 10 a displaceable platen-frame, means for conducting a multi-ply longitudinally fan-folded web to the platen, and means for shifting carbons between the plies of the web to fresh 15 portions of the web during the platen-displacing operation, of means for splitting the plies of the web, said last-mentioned means including a truck operatively connected to the platen-frame, by means of a telescoping device effective to move the truck rearwardly 20 when the platen is lowered to its normal position, said telescoping device including a tube pivotally mounted on said truck, a shaft collapsibly mounted in said tube and having one end pivotally mounted in the platen-frame, and means for positively restoring the 25 position of the truck to its normal position near the platen, when the platen is displaced to its elevated position.

10. The combination with a typewriting machine having a platen revolvably mounted in a displaceable platen-frame, means for conducting a multi-ply longitudinally fan-folded web to the platen, and means for shifting carbons between the plies of the web to 30 fresh portions of the web during the platen-displacing operation, of means for splitting the plies of the web, said last-mentioned means including a truck operatively connected to the platen-frame, by means of a telescoping device effective to move the truck rearwardly when the platen is lowered to its normal position, said telescoping device including a tube pivotally mounted on said truck, a shaft collapsibly mounted in said tube and having one end pivotally mounted in the platen-frame, and means for positively 35 restoring the position of the truck to its normal position near the platen, when the platen is displaced to its elevated position, said last-mentioned means including a pawl pivotally mounted at the end of said tube, and a notch at the end of said shaft, said notch engaging with the pawl to draw on the tube, thereby 40 restoring the position of the truck.

11. The combination with a typewriting machine having a platen, a platen-frame therefor, a device for elevating said platen by rocking said platen-frame, and a web-course at the introductory side of the platen 45 for conducting a longitudinally fan-folded web, to the platen, said course having rails for guiding a carbon-carrier arranged to reciprocate upon said rails, of means movable relatively to said carbon-carrier for slitting

the plies of the web at the folds thereof, said last-mentioned means including a truck arranged to reciprocate upon said rails, means connected to said elevating device for operating said truck during the platen-lowering operation, and a plurality of knives detachably mounted on said truck.

12. The combination with a typewriting machine having a platen, a platen-frame therefor, a device for elevating said platen by rocking said platen-frame, and a web-course at the introductory side of the platen for conducting a longitudinally fan-folded web to the platen, said course having rails for guiding a carbon-carrier arranged to reciprocate upon said rails, of means movable relatively to said carbon-carrier for slitting the plies of the web at the folds thereof, said last-mentioned means including a truck arranged to reciprocate upon said rails, means connected to said elevating device for operating said truck during the platen-lowering operation, a plurality of knives detachably mounted on said truck, a knife-retaining plate overlying said truck, the truck having a platform and holes therein for receiving studs fast to the plate, and means for locking said studs to said platform.

13. The combination with a typewriting machine having a platen, a platen-frame therefor, a device for elevating said platen by rocking said platen-frame, and a web-course at the introductory side of the platen for conducting a longitudinally fan-folded web, having a plurality of plies, to the platen, said course having rails for guiding a carbon-carrier arranged to reciprocate upon said rails, of means for slitting the plies of the web at the folds thereof, said last-mentioned means including a slitting truck arranged to reciprocate upon said rails, relatively to said carbon-carrier, truck-operating means connected to said elevating device, said truck including a plate, wheels under said plate to facilitate the sliding of the truck, knives on said truck interleaved with the plies of the web, said knives being rockably mounted on studs, the studs being mounted on cross-rails fast to the plate, and means for simultaneously locking all the knives in either effective or ineffective position, said last-mentioned means being also effective to lock the studs on which the knives are rockably mounted to said cross-rails.

14. In a fan-fold typewriting machine having a platen and means for elevating the same, a slitting truck, arranged to reciprocate toward and away from said platen, designed to separate the plies of a longitudinally fan-folded web previously to being inserted around the platen, and means for operatively connecting said platen-elevating means to said slitting truck in a manner

to afford the movement of the truck away from the platen when lowering the platen to its normal position.

15. In a fan-fold typewriting machine having a platen and means for elevating the same, a slitting truck, arranged to reciprocate toward and away from said platen, designed to separate the plies of a longitudinally fan-folded web previously to being inserted around the platen, and means for operatively connecting said platen-elevating means to said slitting truck in a manner to afford the movement of the truck away from the platen when lowering the platen to its normal position, said last-mentioned means including a shaft pivotally mounted on the platen-elevating means, a tube pivotally mounted on said truck, and a pawl adjustably mounted on said tube, said pawl being effective to engage with the end of the shaft when the same is pushed toward the pawl.

16. In a fan-fold typewriting machine having a platen and means for elevating the same, a slitting truck, arranged to reciprocate toward and away from said platen, designed to separate the plies of a longitudinally fan-folded web previously to being inserted around the platen, means for operatively connecting said platen-elevating means to said slitting truck in a manner to afford the movement of the truck away from the platen when lowering the platen to its normal position, said last-mentioned means including a shaft pivotally mounted on the platen-elevating means, a tube pivotally mounted on said truck, and a pawl adjustably mounted on said tube, said pawl being effective to engage with the end of the shaft when the same is pushed toward the pawl, and means for releasing said pawl upon reaching a predetermined position of the truck, thereby permitting the shaft to collapse further into the tube.

17. In a fan-fold typewriting machine having a platen and means for elevating the same, a slitting truck, arranged to reciprocate toward and away from said platen, designed to separate the plies of a longitudinally fan-folded web previously to being inserted around the platen, and means for operatively connecting said platen-elevating means to said slitting truck in a manner to afford the movement of the truck away from the platen when lowering the platen to its normal position, said last-mentioned means including, in combination, a truck having slitting knives thereon, means for moving the truck away from the platen when the same is lowered to its normal position, and means for controlling the travel of said truck.

18. In a fan-fold-web typing machine, the combination of a platen, a carbon-holder at the intake side of the platen movable to shift the carbons when the platen is displaced, a web-splitter, and means operatively connected

to the platen for displacing the same and causing said splitter to split the web-folds, after the completion of the carbon-shifting operation.

19. In a fan-fold-web typing machine, the combination of a platen, a carbon-holder at the intake side of the platen, a web-splitter reciprocable between the platen and the carbon-holder, and means operatively connected to the platen for displacing the same and causing said splitter to split the web-folds between the platen and the carbon-holder.

20. In a fan-fold-web typing machine, the combination of a platen, a carbon-holder at the intake side of the platen, a web-splitter reciprocable between the platen and the carbon-holder, and means operatively connected to the platen for displacing the same and causing said splitter to split the web-folds between the platen and the carbon-holder, said splitting means including a displaceable platen-frame, a set of splitting knives, and means loosely connecting said platen-frame to said set of knives to operate the knives effectively only during the restoration of the platen.

21. In a fan-fold-web typing machine, the combination of a platen, a carbon-holder at the intake side of the platen, a web-splitter reciprocable between the platen and the carbon-holder, and means operatively connected to the platen for displacing the same and causing said splitter to split the web-folds between the platen and the carbon-holder, said carbon-holder being movable towards and away from said splitter.

22. In a fan-fold-web typing machine, the combination of a platen, a carbon-holder at the intake side of the platen, a web-splitter reciprocable between the platen and the carbon-holder, means operatively connected to the platen for displacing the same and causing said splitter to split the web-folds between the platen and the carbon-holder, said splitting means including a displaceable platen-frame, a set of splitting knives, and means loosely connecting said platen-frame to said set of knives to operate the knives effectively only during the restoration of the platen, and a stop for limiting the splitting movement of said splitter.

23. In a fan-fold web typing machine, means for stripping carbons interleaved with plies of the web, and means for automatically splitting the folds of the web while the web is stationary after the stripping operation is completed.

24. In a fan-fold web typing machine, mechanism for operating upon the web, and web-slitting means having connections with said web-operating mechanism for automatically slitting the folds of the web while it is stationary.

25. In a fan-fold web typing machine, a carbon-carrier, mechanism for straightening

out the web for allowing the stripping of carbons by said carbon-carrier, and web-slitting means having connections with said straightening-out mechanism for actuating the slitting means to slit the folds of the web.

26. In a fan-fold web typing machine, the combination with a platen-carriage, a platen-frame and a platen displaceably carried by said frame in the platen-carriage, of a web-slitter, and an operative connection between the platen-frame and said web-slitter to afford movement of the web-slitter by the return movement of the platen into the platen-carriage.

15 27. In a fan-fold web typing machine, the combination with a platen-carriage, a platen-

frame and a platen displaceably carried by said frame in the platen-carriage, of a web-slitter, and an operative connection between the platen-frame and said web-slitter during 20 a portion of the return movement of the platen into the platen-carriage.

28. In a fan-fold web typing machine, the combination with a platen-carriage, a platen-frame and a platen displaceably carried by said frame in the platen-carriage, of a web-slitter, and means for automatically moving the web-slitter to slit the web a predetermined distance during the return movement of the platen into the platen-carriage. 25
